ANCHORING DEVICE

Joseph H. Molat, New York, N. Y.

Application February 1, 1945, Serial No. 575,643

3 Claims. (Cl. 85—2.4)

1

My invention relates to anchoring devices of the type employed for attaching objects to walls made of concrete, brick or the like.

One of the objects of my invention is to provide an anchoring device of the class described which shall be of such improved construction that the object may be attached to a wall even when the attaching holes therein do not line up exactly with the anchoring device inserted in the wall, allowing for variations of alignment in all directions.

Another object of my invention is to provide an anchoring device of the class described which shall comprise relatively few and simple parts, which shall be easy to assemble and use and which at the same time shall possess a high degree of efficiency and effectiveness in use.

Still another object of my invention is to provide an anchoring device of the class described which shall be so constructed and arranged that objects attached to the ceiling thereby and depending therefrom will be plumb even when the attaching holes in the object are not in exact alignment with the anchor device in the ceiling.

Further objects of my invention will become apparent in the detailed description thereof to follow or will be hereinafter pointed out.

In the accompanying drawing,

Fig. 1 is a cross-sectional view through a portion of a wall showing the anchoring device of my invention in position for effective use;

Fig. 2 is a front elevational view thereof;

Fig. 3 is a view taken substantially along the line 3—3 of Fig. 1;

Fig. 4 is a cross-sectional view similar to Fig. 1, but illustrating a modified form of my invention; and

Fig. 5 is a view taken substantially along the line 5—5 of Fig. 4.

Referring now in detail to the drawing I have shown a wall anchoring device constructed and arranged in accordance with my invention and illustrating the same as inserted in a wall W in the customary manner of inserting anchoring devices. The wall W may be of brick, concrete or any other well known wall material and the anchoring device comprises a tubular member 10 of rigid metallic material of the nature of iron having a through axial opening 11. The member 10 is provided, at its inner end, with an enlarged outwardly flared end 10a. The wall portions 10b and 10c, extending from the flared end 10a to the outer end, surrounding the opening 11 are outwardly tapered, as shown, the purpose and function of which will soon become apparent.

2

The portion 10d of the wall surrounding the opening 11 at the junction of the end 10a and tapered wall portion 10b is concaved to serve as a seat for a correspondingly curved portion 15a of the enlarged head 15b of a rigid metallic member 15 freely received within the opening 11. It is noted that the shank portion of the member 15 is provided with an internally threaded axial opening 16, and that the outside diameter of the said shank portion is considerably less than the opening 11 so that it may move freely therein. The enlarged head portion 15b limits the axial movement of the member 15. Due to the mating seating arrangement of the correspondingly curved portions 15a and 10d, the member 15 may pivotally move in all directions, providing a universal mounting for the member 15.

The shank portion of the member 10 may be surrounded by a soft metallic sheath 20, as is known and customarily employed in the art, for retaining the member 10 firmly in the wall W.

To attach an object to the wall W by means of the anchor device just described it is merely necessary to pass a suitable screw 25 through a corresponding attaching opening in the object and thread the same in the threaded opening 16 of the member 15 as clearly shown in Fig. 1 of the drawing. The enlarged head 15b of the member 15 will hold the said member captive, while the head of the screw 25 will maintain the object against the wall W.

In accordance with my invention, as above described, if the opening in the object through which the screw is passed is out of alignment with the opening 20 in the member 15, the said member 15 will adjustably pivotally move itself within the opening 11 and thus the object may be attached without drilling new openings in the object or removing and repositioning the anchor device.

It is also noted that should the anchor device be positioned in a ceiling or top wall for the purpose of hanging an object therefrom, the said object will always hang straight and in plumb due to the construction of my anchor device as described above which permits universal free movement of the member 15 within the opening 11.

To provide a better frictional grip of the head 15b of the member 15 against the seat 10d, when the screw 25 is tightened, I may provide circumferentially spaced ribs 19 on the convexed portion 15a of the member 15.

In Figs. 4 and 5 I have shown a modified form

of my invention in which the construction of all the parts are identical with those illustrated in the Figs. 1 to 3 form of invention except that the opening 31 in the member 30, corresponding to the opening 16 in the member 15, runs axially clear through the said member 30 and a countersunk portion 32 is provided in the enlarged head portion of the member 30. In this form of my invention a screw member 40 is inserted in the opening 31 from the inner end before the anchor member is inserted in the wall W, the head 40a thereof being received in the corresponding countersunk portion 32 and the shank portion of the screw 40 extending beyond the wall W. This extending shank portion of the screw 40 is adapted to pass through the opening in the object and a nut 50 and washer 51 placed thereon to hold the said object in firm attachment to the wall W. In this form of my invention, as in the Figs. 1 to 3 form, the member 30 is freely mounted for universal pivotal movement to compensatingly adjust itself to disalignment between the opening in the object and the axis of the opening of the anchor device in the wall W.

In accordance with the provisions of the patent statutes, I have herein described the principle and operation of my invention, together with the construction which I now consider to represent the best embodiment thereof, but I desire to have it understood that the construction can be carried out by other means. Also while it is designed to use the various features and elements in the combination and relations described, some of these may be altered and others omitted without interfering with the more general results outlined, and the invention extends to such use.

Having described my invention, what I claim and desire to secure by Letters Patent is:

1. For use in attaching an object to a wall or ceiling, an anchor device of the character described comprising a relatively rigid first tubular member, a soft metallic sheath surrounding said first tubular member, the said first tubular mem-

ber and sheath being adapted to be received in an opening in said wall and frictionally retained therein, the inner wall of said first tubular member having a relatively enlarged head portion at the inner end thereof and a relatively constricted portion, the said relatively constricted portion being tapered outwardly from said head portion to the opposite end thereof, a second rigid member comprising an enlarged head portion and a shank portion, said second member being disposed within said first member with the enlarged head portion of said second member nested within the enlarged head portion of said first member and with said shank portion nested within the constricted portion of said first member, the enlarged head portion of said second member being larger than said constricted portion of said first member whereby the axial movement of said second member will be limited in an outward direction, the size of said shank portion of said second member being such as to provide a free space between the outer wall thereof and the inner wall of said constricted portion of said first member to permit free adjustable angular movement of said second member with respect to said first member for the purposes set forth and means for attaching an object fastening screw member or bolt to said second member.

2. An anchor device according to claim 1 in which the enlarged head portion of said second member is provided with a plurality of ridges to provide a better frictional grip on the enlarged head portion of said first member when said object is attached to said wall.

3. An anchor device according to claim 1 in which the said second member is of tubular construction and in which the means for attaching an object fastening screw member or bolt to said second member comprises a bolt passing through the opening in said second member, the head of said bolt resting in the enlarged head portion of said second member.

JOSEPH H. MOLAT.
